CLAIM

The ornamental design for a mobile phone holder as shown and described.

DESCRIPTION

FIG. 1 is a perspective view of a mobile phone holder showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the mobile phone holder shown in an environment of use where the mobile phone holder is in a configuration of use;

FIG. 10 is an enlarged view of portion 11 shown in FIG. 1; and,

FIG. 11 is an enlarged view of portion 11 shown in FIG. 5. The dash-dash broken lines in the drawings depict portions of the mobile phone holder. The dot-dash broken lines represent boundaries of the enlarged portions. The broken line showing of a mobile phone and mount in FIG. 9 depicts environment for the mobile phone holder. All broken lines form no part of the claimed design.

1 Claim, 11 Drawing Sheets
